UNITED STATES PATENT OFFICE.

JOSIAH N. KNOX, OF EVANSVILLE, INDIANA.

BIER OR COFFIN STOOL.

SPECIFICATION forming part of Letters Patent No. 291,605, dated January 8, 1884.

Application filed July 23, 1883. (No model.)

To all whom it may concern:

Be it known that I, JOSIAH N. KNOX, of Evansville, in the county of Vanderburg and State of Indiana, have invented certain new 5 and useful Improvements in Bier or Coffin Stools for Undertakers' Use; and I do hereby declare that the following is a clear and exact description thereof, reference being had to the accompanying drawings, and to the letters of 10 reference marked thereon, which form a part of this specification.

The invention relates particularly to certain improvements in that class of stools for closing up into a more convenient and compact form when not in use than when they are 15 in use, and, when surmounted on top by a suitable arrangement, may be used for other purposes than for coffin-supports, and is equally applicable to a camp-stool or other seat. 20 The nature of my invention consists in the combination of the several parts hereinafter to be described, and which will be specifically set forth in the claims.

In the drawings, Figure 1 represents a side 25 elevation when closed and not in use; Fig. 2, a side view when being adjusted for use; Fig. 3, closed and ready for use.

The letter A indicates the vertical central shaft or support of the stool, to which are attached suitable legs, D D and E E, for holding the same in proper and substantial position. This vertical shaft A is made to pass vertically clear through the stool, and may be made round on the lower end, and is 30 mounted on top by a horizontal cross-piece, C, supported by suitable bracket-arms, B B, for the purpose of giving the same required strength. The legs D D are firmly secured to the vertical shaft A at or near the center, and are formed with a hollow recess on the under 35 side, as shown by the dotted lines F F, for the purpose of receiving and holding in proper position the bracketed legs E E when closed and not in use. In the center of these bracketed legs D D is made a slotted aperture or mortise at G, on the under side, for the purpose of receiving or holding the adjustable or movable legs E E in position when brought 40 in place for use. These bracketed legs E E are provided with a cross-bar, H, at or near the bottom, which bar is provided in the center with a

socket or hole for the purpose of receiving the lower end of the vertical shaft A. They are also provided on the upper side in the center with a slotted mortise to correspond in width 55 to the thickness of the legs D D, so that when brought into position for use it will hold firm and prevent any lateral motion. They are also provided with a suitable hole through the upper center at J, through which the vertical 60 shaft A passes. Placed on this vertical shaft A, under the center of the bracketed legs E E, is a suitable metal or coiled-wire spring, S, fastened at the lower end of the shaft A, as shown in the drawings, which spring constantly 65 presses upward against the under side of the bracketed legs E E, for the purpose of always keeping them in desired position, and for the purpose of making the stool self-closing when the legs E E are properly adjusted 70 to position. This spring S may, however, by suitable arrangement, be placed on the shaft above the legs E E, and by proper attachment be made to draw or pull them into position rather than by upward pressure, as 75 shown in the drawings.

The operation of my invention will be readily understood in connection with the above description, and is as follows: When closed, as shown in Fig. 1, the operator drawing 80 down the adjustable legs E E to the position as shown in Fig. 2, and adjusting them at right angles with the fixed legs D D, they are quickly thrown or drawn up on the shaft by the spring and received in the slotted recess 85 at G, which holds them securely in position and ready for use.

Having thus fully described my invention, what I claim, and desire to secure by Letters Patent, is—

1. The combination, in a stool-frame, of a main supporting-bracket, having its legs grooved on their inner side, with an auxiliary bracket constructed and arranged substantially as set forth, whereby it may be set and 95 held at right angles to the main bracket or placed in the same plane and received in the grooves therein, all as and for the purposes set forth.

2. The combination, in a coffin bier or stool, 100 of cross-bar C, legs B, shaft A, and legs D D, the latter being grooved out and notched, as

shown at F and G, with legs E E, having cross-bar H, all constructed and arranged to operate as and for the purposes set forth.

3. A coffin bier or stool composed of cross-bar C, supports or legs B B, shaft A, spring S, adjustable legs E E, having cross-bar H, said parts being constructed and arranged to operate substantially as and for the purposes set forth.

In testimony that I claim the foregoing as to my own I affix my signature in the presence of two witnesses.

J. N. KNOX.
